UNITED STATES PATENT OFFICE

2,064,682

ANNEALING APPARATUS

William H. Nickerson, Newton Center, Mass.

Application September 21, 1935, Serial No. 41,582

3 Claims. (Cl. 263—8)

The immediate object of the present invention is to provide an apparatus by which hardened steel shoe shank stiffeners having integral prongs may be annealed at those parts only which comprise the prongs and without diminishing the hardness and spring temper of the body of the article. Shank stiffeners of this character are described in the pending applications for United States Patent of Stacy M. Nickerson, filed December 1, 1934, Serial No. 755,594, and filed April 3, 1935, Serial No. 14,453. The materials of which such stiffeners are made are susceptible to hardening and tempering by heat treatment to a desirable condition of resilient stiffness; but if the integral prongs of such stiffeners have the same degree of hardness they are too brittle to be clinched with uniform success in the sole of a shoe and are liable either to break off or fail to curl over at the point when attempt is made to clinch them. Hence the prongs are annealed to a condition of softness permitting them to be curled over without the liability of breakage, before being sold for use. The machine or apparatus which I have devised for carrying the foregoing object into effect, and have shown in the drawings herewith furnished, is provided with means for creating zones of heat and means for propelling pronged shank stiffeners of the character described in the paths which bring their pronged ends into such zones of heat, and retain them there for a long enough period to soften the prongs; and the machine also includes means to limit the heating effect to the prongs and adjacent ends of the stiffener.

While my primary object is as here above stated, I would have it understood that the protection I claim is not necessarily limited to a machine combination capable of accomplishing only that object and no other. On the contrary, the invention includes all aspects and subcombinations of the novel features of disclosed apparatus, and equivalents thereof, for any purposes and uses to which the same may be successfully applied.

Defining now the specific machine depicted in the drawings, but without thereby restricting my invention to narrower limits than those indicated in the foregoing statements and the appended claims, I am first describing the drawings.

In the drawings,—

Figure 1 shows a side elevation of the machine.

Figure 2 shows a plan view of the machine.

Figures 3 and 4 show detail cross sections taken

on lines 3—3 and 4—4, respectively, of Figure 1, and drawn on a larger scale.

Figure 5 is a perspective view of parts of the machine at the point where the ends of the shank stiffeners are first brought into the heating zone. 5

Figure 6 is a perspective view of a pronged shank stiffener after undergoing the treatment performed by the machine.

Like reference characters designate the same parts wherever they occur in all the figures. 10

The operating parts are supported on the frame work which is here shown as consisting of two parallel longitudinal members 10, made of angle irons, connected cross members 11 and 12 at opposite ends of the longitudinals, and legs 13, 15 14 and braces 15, 16 secured to each longitudinal. The righthand end of the machine (with respect to Figures 1 and 2) is the loading end and comprises a supporting rail or track 17 and a limit or guide bar 18, at each side of the longitudinal middle line. The rails or bars 17 and 18 at each side are connected together by bolts 19 and spaced apart from one another by intermediate washers or sleeves 20 surrounding the bolts 19. Brackets 21 support each outer bar 18 and are supported in turn by the frame in a manner later described. 20

These supporting and guiding rails lead to heating means or furnaces which are organized to deliver heat in narrow zones extending parallel to one another lengthwise of the frame work for 30 a distance which, in conjunction with the speed of feeding of the articles to be annealed, produces the required heating effect on such articles. Each furnace or heat generator comprises a tube 22 adapted to receive and convey an inflammable 35 gas or vapor and pierced with a row of holes 23 along one side, which holes have suitable diameter to enable the gas escaping from them to support flames when ignited. The diameter and spacing of these gas outlet orifices may be of 40 any desired values, determined according to well understood principles, which will produce the desired heating effect and the desired continuity or gradations of temperature throughout the length of the tubes, having regard to the character 45 of gas or vapor employed, the pressure under which it is supplied, and the temperature required to be imparted to the articles operated upon.

The gas tube is supported on a series of bed 50 blocks 24 and clamped between baffle plates 25 and 26, one of which is connected directly to a lip or flange 27 of the bed block and the other to a bracket 28 which in turn is secured to the bed block; all as shown in Figure 4. The baffle plates 55

extend throughout the length of the gas tube, or at least so much of it as contains jet orifices, and make tangent contact with the tube at opposite sides. They preferably converge somewhat upwardly, the plate 25 (which is at the side of the tube toward the middle line of the machine) being upright and the opposite plate inclined toward it; and the tube 22 is placed preferably so that the jet orifices are directed on an inclination toward the plane of the baffle plate 25. The upper edges of these plates are nearly at the same level, but the outer plate 26 extends enough above the inner plate to serve as a gauge or guard to prevent outward displacement of the adjacent end of the shank stiffener under treatment. The plates together confine the burning gas to a zone limited by the width of the slit between their upper edges. They also absorb and dissipate such heat from the flame as is not directly carried away by the rising gases.

The inner rails 17 at the loading end of the machine and the inner baffles 25 of the furnaces support the shank stiffeners S undergoing treatment. Such stiffeners are strips of sheet steel having great enough carbon content to be susceptible of hardening, which have been shaped with a longitudinal and transverse arched formation and cut adjacent to their ends to form integral tapered prongs P. After having been so cut and shaped while in soft condition the shank stiffeners have then been hardened and tempered, and when brought to the treatment of this apparatus are suitable for use in shoes except that the prongs are too hard and brittle. But after passing through the apparatus the shank stiffeners emerge with their prongs so annealed and softened that they may be bent without breaking. Incidentally the material adjacent to the prongs is annealed also. The annealed portions are represented in Fig. 6 by the shading applied to the ends of the shank stiffener there depicted.

The rails of the loading end are located to support such stiffeners in a transverse position with their ends between the outer or guard rails 18 and their prongs in the space between the adjacent rails 17 and 18, while resting adjacent to their pronged ends on the rails 17, as indicated by the broken line representation S¹ of such a stiffener in Figure 5. From the loading part of the machine the stiffeners pass to the furnaces or heating zones, where they are supported on the upper edges of the baffle plates 25 and their ends (including their prongs) overhang the spaces between the baffle plates at each side of the machine. The outer baffle plates extend across the ends of the stiffeners and, although ordinarily not touching them, are potential guards preventing any considerable displacement of the stiffeners to either side.

The inner baffle plates prevent contact of the flame with any part of the shank stiffeners except their overhanging ends. Thus even though the ends of the stiffeners may be brought to a red heat during their passage through the zones of fire, the annealing effect is limited approximately to those portions of the stiffeners between their extremities and the points at which the stiffeners make contact with the inner baffle plates.

The shank stiffeners are propelled by two conveyor chains 29 and 30 which pass around sprocket wheels 31 and 32 at the loading end of the machine, and also around sprocket wheels 33 and 34 at the delivery end. The upper stretches of these chains pass close to the inner baffle plates

of the two heaters, and are supported, through a part at least of their length, sufficient to prevent too much sagging, by horizontal plates or strips 35 which rest on the lips 27 of the bed blocks 24 and are embraced between the inner baffle plates 25 and uprights 36 secured to the inner faces of the bed blocks.

The links of these chains carry pins or fingers 37 which rise to a height sufficient to engage and push the shank stiffeners resting on the supporting rails 17 and baffle plates 25. The stiffeners are not carried by these chains; but are pushed by them while resting on other supports. A suitable construction of chain link is shown in detail in Figure 5, each link having a hook 38 at one end which makes a hinged interlock with a bar on the adjacent edge of the next link. In their middle parts the links have a solid portion of sufficient thickness to receive and hold the pins rigidly. The links are considerably longer than the width of the shank stiffeners, whereby sufficient space is provided between adjacent pins to receive the stiffeners without requiring particular care on the part of the attendant who loads the machine to ensure correct placement.

An electric motor 39 drives the chains through a belt 40, pulley 41, worm 42 on the shaft of this pulley, and worm wheel 43 secured to a shaft 44 to which the sprocket wheels 33 and 34 also are secured; the other sprocket wheels being secured to a shaft 45 which turns idly. The shaft of the worm 42 and pulley 41 is supported by a bracket 46 which is secured to one of the longitudinal members of the frame work.

Shank stiffeners vary in length by as much as one-half inch, or more, between the shortest and longest sizes. In order to accommodate the different grades and ensure their symmetrical and proper location with respect to the heating means, the supporting rails and heating means at one side of the machine (in this case the rear side with respect to Figure 2), are adjustable transversely. For this purpose the brackets 21 and bed blocks 24 which support the rear rails and heater are secured to a bed plate or strip 47 which rests on the rear longitudinal frame member. The bearing blocks 48 and 49 for ends of the shafts 44 and 45, respectively, are also secured to this bed plate. Adjusting screws 50 and 51 are threaded into the bearing blocks 48 and 49, respectively, and are confined against endwise movement by notched brackets 52 secured to and rising from the adjacent underlying longitudinal frame member. Thus by turning these screws in one direction or the other, the bed plate with its supported guides etc. is moved to front or rear. The brackets and bed blocks for the guides and heater at the other side of the machine are immovably fastened to the frame, being secured to a bed plate 53 which in turn is secured to the frame. The chain 30 confined between the plate 25 and uprights 36 of this adjustable assemblage is moved with the assemblage, and in order to maintain the necessary alignment between this chain and its sprockets 32 and 34, the latter are equally adjusted along their shafts 44 and 45. It will be noted in Figs. 2 and 3 that the hubs of the several sprocket wheels are secured to their shafts by set screws 53a, which may be tightened to secure the sprockets anywhere along the length of the shafts, and loosening of which permits shifting of the sprockets. The shafts themselves are not displaced endwise by the above described adjustments, as they are equipped with collars 75

54, secured to them by set screws as shown in Figs. 2 and 3, which flank the shaft bearings 55 and 56, and these bearings are secured immovably to the frame.

5 Gas is supplied to the pierced tubes by a pipe 57 which is connected to the non-adjustable jet tube by a rigid elbow 58 and to the adjustable jet tube by a flexible pipe section 59. Both jet tubes are, of course, closed at the end remote 10 from their receiving end so that their only outlets for gas are the jet orifices 23.

Machines containing the principles of that above described may be made in a wide variety of dimensions and proportions. The length of 15 the gas jet tubes, the intensity of the flame, and the rate of travel of the propelling fingers are such that the prongs are brought to a dull red heat and then withdrawn from the flame before they have become burned or overheated. After 20 leaving the heating zones the shank stiffeners are carried by the pins over the sprockets 33 and 34 whence they drop into a receptacle in which they are allowed to cool gradually. I have found that with a flame zone about three feet long 25 and a feeding speed of about six feet per minute, so that the pronged ends of the shank stiffeners remain in the heating zones about one-half minute, satisfactory heating effects are obtained and a sufficiently rapid production is obtained. If 30 the propelling pins are half an inch apart (and they may be closer together than this), the maximum production rate is at least 144 units per minute. This rate is as fast as a single operator feeding the machine by hand can main- 35 tain comfortably over extended periods. Thus the speed of feeding the machine is the factor which practically determines the length of the heating zones. They can be made of suitable length to accommodate any other practicable 40 feeding speed.

The heating means is not necessarily limited to gas but may be anything substantially equivalent, and may be used with, if necessary, an appropriate modification in the dimensions and 45 proportions of the parts, speed of travel of the work pieces, etc., according to the principles herein set forth.

What I claim and desire to secure by Letters Patent is:—

50 1. A heat generator for annealing purposes

comprising a tube adapted to contain inflammable gas or vapor, having a row of jet orifices along one side, baffle plates tangent to the tube at opposite sides of the row of jets, arranged to confine the products of combustion and form 5 a slot between their edges through which the products of combustion escape, and supporting means to which said baffle plates are secured and by which, in conjunction with the plates, the tube is clamped in place. 10

2. An apparatus for annealing the pronged ends of hardened steel shank stiffeners for shoes comprising a supporting structure including two separated parallel longitudinal members, bed blocks mounted in longitudinal alinement on each 15 of said members, tubes supported on the bed blocks of each member in parallel with one another, baffle plates secured to the bed blocks of each member at respectively opposite sides of the tube supported on the bed blocks of the 20 respective member, the baffle plates extending longitudinally of the tube and being relatively inclined convergently to one another above the tube and in engagement with the latter whereby 25 to secure the tube on the bed block, the tube being adapted to convey inflammable fluid and having burner outlets directed toward the space between the baffle plates, the inward members of each pair of baffle plates being separated from one another by a distance shorter than the length 30 of the shank stiffener to be treated, and conveyer means organized to propel lengthwise of the machine shank stiffeners supported by the inner baffle plates.

3. In an annealing machine, a heating furnace 35 comprising a supporting structure, a tube adapted to convey inflammable fluid, said tube resting on said supporting structure in a substantially horizontal position, and baffle plates secured to said supporting structure at respectively opposite sides 40 of the tube, extending lengthwise of the tube and above the tube convergently toward one another, being secured in tangent contact with the tube whereby to position and secure the tube in place on the supporting structure, and being 45 spaced apart from one another at their upper edges, the tube having orifices in its upper portion directed toward the space between the upper edges of the baffle plates.

WILLIAM H. NICKERSON. 50
